FITTING FOR WIRE ROPE AND STRANDS

William J. Gilmore, Adrian, Mich., assignor to
 American Chain & Cable Company, Inc.,
 Bridgeport, Conn., a corporation of New York

Application December 15, 1947, Serial No. 791,777

1 Claim. (Cl. 24—123)

1

This invention relates to fittings for wire rope and strands.

Fittings on ferrous rope or strand are advantageously made in the form of sleeves which are swaged or cold worked onto the rope thus avoiding excessive heat which would damage the rope. However, as a commercial practice, they are very difficult to apply with the assurance that the hold will be sufficient if they are subjected to a stress sufficient to break the rope.

It is therefore a primary object of the present invention to provide a fitting which can be applied on a commercial production basis to develop the full strength of the rope or strand to which it is applied.

Referring now to the drawings:

Fig. 1 is a view showing a cylindrical blank before the first operation thereon;

Fig. 2 shows a similar blank with indentations formed therein as a preliminary step to the fabrication of the fitting, and with a longitudinal hole drilled therethrough;

Fig. 3 is a section taken on line 3—3 of Fig. 2;

Fig. 4 is a view of the fitting after assembly around the strand and after completion of the 25 swaging operation;

Figs. 5, 6 and 7 are sections on lines 5—5, 6—6, and 7—7 respectively of Fig. 4; and

Fig. 8 is a view of a modified blank used in the practice of this invention.

This invention is described in connection with ferrous strand, for ease of description, and because it is particularly well adapted to strand. It has always been difficult to grip strand tightly enough, and the failures occur as slippage of the fitting on the wire, rather than as breaking of the wire. However, it is to be understood that the invention is not limited to strand, but can be applied to rope and cable with equal facility.

The example shown is a plain cylindrical fitting, utilized as an ending. As a preliminary step, a solid cylindrical piece of metal 10, preferably with a frusto-conical end 11 is pressed or punched so as to produce the exterior contour shown in Figs. 2 and 3. This embossing consists of impressing in the cylindrical surface a series of depressions 12 shown as being segments of cylindrical surfaces. It will be noted that they occur in pairs, each succeeding pair being spaced 90° around the periphery of the blank, and all preferably equally spaced from each other. The making of these depressions throws the metal of the blank into a sort of flattened indented shape, as best seen in Figure 3.

After the exterior of the blank has been deformed as above described, a bore 13 is formed

2

therethrough, which may be cylindrical, but preferably has a tapered bell mouth at 14, the bore being sufficiently large to receive the strand to be secured therein.

5 A strand 15 is inserted in the bore, and the entire fitting, or at least as much of it as surrounds the strand, is then subject to cold working by swaging, so that it becomes cylindrical. The depressions in the surface are substantially obliterated, and the strand is tightly held by such swaging.

10 The most important feature of this invention is the arrangement of the depressions and the resultant deformation of the strand under swaging. As shown in Figures 4 to 7 inclusive, the swaging results in a deformation of the strand, by actual displacement of the wires thereof, so that it takes on an oval cross-section directly under each pair of depressions. However, the next adjacent pair of depressions, which is 90° around the periphery of the blank, results in an oval the major axis of which is disposed at right angles to the axis of the first-mentioned oval.

15 As the wire of which the strand is made is relatively stiff and hard, the deformation is sufficient to render it impossible to pull the strand out of the fitting. There is considerable friction opposing such withdrawal, but it can be inferred that the development of the full strength of the 20 joint depends upon the rapid change from one oval to another along the axis of the fitting. This inference is justified by the entire absence of slippage before failure, in testing, as distinguished from swaged fittings without the depressions. This inference is also supported by the 25 fact that the degree of swaging is not overly critical.

30 There is one feature of this invention which is not inherent in the construction, but nevertheless important in the shown structure. As can be seen in Figs. 5 and 6, the material of the sleeve is thickest across the minor axis of the oval. This is as it should be, as the metal is 35 amply strong in tension, and will not rupture in region A as an attempt is made to pull the strand out. Furthermore, the thick Section B cannot bend, which prevents the sleeve from distorting in such a manner as to permit the strand to take a more circular form. Such distortion would, of course, if permitted, tend to result in slippage. This construction is in distinction to sleeves having a uniform thickness around a non-circular strand, which must be made thicker all around to prevent such distortion, and are thus heavier than is theoretically necessary.

35 Instead of swaging the depressions 12 into the

blank, it is perfectly feasible to machine them. As an example, in Fig. 8 a blank 18 is shown with arcuate slots 19 milled across the cylindrical surface, to serve the same function as the deformation practiced in the structure shown in 5 the other views. There are possibly other types of blanks which can be used, depending on the desired result, and it is therefore to be understood that the above constructions are illustrative and not limitative, and that the scope of the 10 present invention is to be determined from the appended claim.

I claim:

An article of manufacture comprising a ferrous stranded structure and a sleeve compacted 15 thereon, said sleeve having a substantially cylindrical surface, the bore of the sleeve and the portion of the stranded structure therein having oval cross-sections at spaced points along the 20 length, the major axis of the oval cross-section at one point being at substantially right angles to the major axis of the oval cross-section at the other point the transition from one oval cross-section to the other being in the nature of

a widening to a substantially circular cross-section and flattening to the other oval cross-section.
